UNITED STATES PATENT OFFICE

2,492,110

RETRACTING TYPE THEATER CHAIR

Joseph G. Prosser and Thomas W. Prosser, Pasadena, Calif., assignors to American Seating Company, Grand Rapids, Mich., a corporation of New Jersey

Application June 26, 1946, Serial No. 679,358

6 Claims. (Cl. 155—116)

1

The present invention relates to chairs and more particularly to chairs of the retracting type for use in theaters, auditoriums and the like. This application is a continuation-in-part of our co-pending application Serial No. 679,354 filed June 26, 1946.

The primary objects of the invention are to provide an improved chair of the retracting type wherein the occupant may move the seat rearwardly in order to permit others to pass in front of him without his having to rise from the seat; to provide such a chair having a combination link and roller or link and sliding block mechanism for mounting the chair back and seat, which mechanism insures easy and comfortable forward and rearward movements and which is concealed below the level of the chair seat; to provide such a chair which when retracted occupies a minimum of space in the rear of the chair; to provide such a chair having improved means for mounting on spaced chair-supporting standards; and in general to provide such a retracting chair which is efficient in operation, reasonably economical in manufacture and attractive in appearance.

An illustrative embodiment of the invention is shown in the accompanying drawings, wherein:

Figure 1 is a perspective view of a retracting chair showing the chair seat and back in their normal, forward positions for occupancy;

Figure 2 is a perspective view similar to Figure 1 showing the chair seat and back in their retracted positions;

Figure 3 is a fragmentary front elevational view of the left-hand side of the chair;

Figure 4 is an inside elevational view of the same, certain parts being shown in vertical section taken on line 4—4 of Figure 3, and the parts of the operating mechanism being shown in their forward positions;

Figure 5 is a view similar to Figure 4 with the operating parts being shown in their rearward positions of retraction.

Referring now in detail to these drawings wherein like parts are designated by the same numerals in the several views, the retracting chair there shown is mounted on a frame comprising spaced, upright, chair-supporting standards 1 having inwardly projecting lugs 2 thereon provided with vertical stud-receiving slots 3, mounting members 4 having outwardly turned flanges 5 with depending, threaded studs 6 adapted to fit into the slots 3, nut 7 threaded on the lower ends of the studs 6, and a transverse bar 8 secured as by welding to the opposite mount-

2

ing members 4. The frame thus formed is of sturdy and rigid construction. If desired, members 9 (see Figures 1-3) of rubber, cork or other resilient material may be interposed between the flanges 5 of the mounting members and the lugs 2 on the standards for absorbing any vibration of the chair during its retracting and returning movements.

The mounting and operating mechanisms on opposite sides of the chair being of like construction, only one side is shown in Figures 3, 4 and 5 and hereinafter described. The mounting member 4 has a pair of vertically spaced, forwardly-rearwardly extending guide tracks or ways, the upper way being designated 10 and the lower way being designated 11 on the drawing. A combination seat and back support or carrier 12 bears in the lower way 11, being provided with a sliding block or roller 13 moving forwardly and rearwardly in this way 11.

A rear supporting link 14 has its lower end pivotally connected to the mounting member 4. A side plate 15 of generally triangular shape is pivotally connected to the upper end of the rear supporting link 14 and to the rearward end of the carrier 12. The forward end of the side plate 15 bears in the upper way 10 of the mounting member 4, being provided with a sliding block or roller 16 movable forwardly-rearwardly in this way 10.

As here shown, the lower track or way 11 is substantially horizontal, while the upper track or way 10 is of arcuate or cammed formation extending rearwardly-downwardly. It will be seen that by this arrangement, when the carrier 12 moves rearwardly in a substantially straight path, the side plate 15 moves rearwardly and is also turned in a clockwise direction as viewed in Figures 4 and 5 about its pivotal connection 30 with the rear supporting link 14.

The chair back 17 is mounted on inwardly turned flanges 18 of the side plates 15 on opposite sides of the chair, as by means of screws 19. The chair seat 20 is provided with seat arms 21 secured to the opposite sides thereof as by means of screws 22, and these seat arms 21 are pivotally connected at 23 to the carriers 12 on opposite sides of the chair. The seat is thus movable forwardly and rearwardly with the carriers 12, and is also turnable about a horizontal axis so that it may be raised in order to facilitate sweeping under the chair. When in its lowered position of occupancy, the seat is supported forwardly of its axis of turning movement by means

of stops 24 on the carriers 12, on which stops the seat arms 21 rest.

An equalizing strut 25 is desirably secured as by welding to the rear supporting links 14 on opposite sides of the chair so that these links are rigidly secured in assembly and move in unison, thus adding to the stability of the structure.

When the chair is retracted, the seat moves rearwardly in a substantially straight path, while the back moves rearwardly and also assumes a near-vertical position thus to minimize the space required for retraction in the rear of the chair. Forward and rearward movements of the chair are stopped by contact of the blocks or rollers 13 and 16 with stop means which comprise the ends 15 of the ways 11 and 10 respectively.

It will thus be seen that a retracting chair has been provided having a novel combination of links and rollers in which the mounting and operating mechanism is located out of sight below the seat level, and which mechanism is arranged for easy and comfortable forward-rearward movements of the chair, and while but one specific embodiment of the invention has been herein shown and described, it will be understood that certain details of the construction shown may be altered or omitted without departing from the spirit of the invention as the same is defined by the following claims, wherein the word "frame" is to be construed broadly enough to include either a unitary assembly or a pair of spaced chair standards whose only rigid connection is the floor upon which such pair of standards is installed.

We claim:

1. In a chair, a frame having at each of its opposite sides a pair of vertically spaced, forwardly-rearwardly extending ways, the lower ways being substantially horizontal and the upper ways being inclined forwardly-upwardly, carriers bearing in the lower ways for forward and rearward movements, a chair seat mounted on the carriers and movable forwardly and rearwardly therewith, a chair back pivotally connected to the carriers movable forwardly and rearwardly with said carriers and turnable about a horizontal axis, a supporting link having its lower end pivotally connected to the frame and its upper end pivotally connected to the back, means on the back bearing in the upper ways for varying the angular inclination of the back relative to the seat during the forward and rearward movements thereof, and stop means for limiting the forward and rearward movements of the carriers.

2. In a chair, a frame having at each of its opposite sides a pair of vertically spaced, forwardly-rearwardly extending ways, the lower ways being substantially horizontal and the upper ways being inclined forwardly-upwardly, carriers bearing in the lower ways for forward and rearward movements, a chair seat mounted on the carriers turnably about a horizontal axis and movable forwardly and rearwardly with the carriers, means on the carriers for supporting the seat in a lowered position for occupancy, a chair back pivotally connected to the carriers movable forwardly and rearwardly with said carriers and turnable about a horizontal axis, a supporting link having its lower end pivotally connected to the frame and its upper end pivotally connected to the back, means on the back bearing in the upper ways for varying the angular inclination of the back relative to the seat during the forward and rearward movements thereof, and stop

means for limiting the forward and rearward movements of the carriers.

3. In a chair, a frame having at each of its opposite sides a pair of vertically spaced, forwardly-rearwardly extending ways, the lower ways being substantially horizontal and the upper ways being inclined forwardly-upwardly, carriers bearing in the lower ways for forward and rearward movements, a chair seat mounted on the carriers and movable forwardly and rearwardly therewith, side plates pivotally connected to said carriers respectively, rear supporting links having their lower ends pivotally connected to the frame and their upper ends pivotally connected to the side plates respectively, a chair back mounted on the side plates, said side plates bearing in the upper ways on the frame for effecting movement of the side plates turnably about a horizontal axis in order to vary the angular inclination of the back relative to the seat during the forward and rearward movements thereof, and stop means for limiting the forward and rearward movements of the carriers.

4. In a chair, a frame having at each of its opposite sides a pair of vertically spaced, forwardly-rearwardly extending ways, carriers bearing in the lower ways for forward and rearward movements, a chair seat mounted on the carriers and movable forwardly and rearwardly therewith, side plates pivotally connected to said carriers respectively, rear supporting links having their lower ends pivotally connected to the frame and their upper ends pivotally connected to the side plates respectively, a chair back mounted on the side plates, the upper ways on the frame being of forwardly-upwardly inclined cammed formation and said side plates bearing in these upper ways for forward-rearward movement and for turning movement about a horizontal axis for varying the angular inclination of the back from a forwardly-downwardly extending position to a substantially vertical position during rearward movement of the back and for opposite turning movement during forward movement of the back, and stop means for limiting the forward and rearward movements of the carriers.

5. In a chair, a frame having at each of its opposite sides a pair of vertically spaced, forwardly-rearwardly extending ways, the lower ways being substantially horizontal and the upper ways being inclined forwardly-upwardly, carriers having rollers bearing in the lower ways for forward and rearward movements, a chair seat mounted on the carriers and movable forwardly and rearwardly therewith, a chair back pivotally connected to the carriers movable forwardly and rearwardly with said carriers and turnable about a horizontal axis, a supporting link having its lower end pivotally connected to the frame and its upper end pivotally connected to the back, means on the back bearing in the upper ways for varying the angular inclination of the back relative to the seat during the forward and rearward movements thereof, and stop means for limiting the forward and rearward movements of the carriers.

6. In a chair, a frame having at each of its opposite sides a pair of vertically spaced, forwardly-rearwardly extending ways, the lower ways being substantially horizontal and the upper ways being inclined forwardly-upwardly, carriers having rollers bearing in the lower ways for forward and rearward movements, a chair seat mounted on the carriers and movable forwardly

and rearwardly therewith, side plates pivotally connected to said carriers respectively, rear supporting links having their lower ends pivotally connected to the frame and their upper ends pivotally connected to the side plates respectively, a chair back mounted on the side plates, said side plates having rollers bearing in the upper ways on the frame for effecting movement of the side plates turnably about a horizontal axis in order to vary the angular inclination of the back relative to the seat during the forward and rearward movements thereof, and stop means for limiting the forward and rearward movements of the carriers.
